VACUUM CLEANER RECEPTACLE

William P. Hunsdorf, Cleveland, Ohio, assignor,
by mesne assignments, to Airway Electric Ap-
pliance Corporation, Toledo, Ohio, a corpora-
tion of Delaware

Application September 30, 1930, Serial No. 485,458
Renewed April 14, 1934

11 Claims. (Cl. 183—51)

My invention relates to vacuum cleaners and has as its object to provide, in combination, a vacuum cleaner and a porous paper dust collecting receptacle, of such construction and arrangement that the handle may be freely moved (if of the movable type) without rupturing the bag at the region where it connects to the fan case exhaust.

Another object is to provide a dust collector bag having an inlet trap extending to a very substantial height within such bag, in an arrangement wherein means is provided to prevent collapsing of the trap without interfering with its normal function of sealing the bag entrance against loss of any dirt during removal from the cleaner.

Another object is to provide a flexible non-collapsible injection tube of sufficient length to extend to a substantial height within the collecting bag, in combination with such a bag having means to protect such tube from becoming embedded in the collected litter within the bag.

Another object is to provide a non-collapsible injection or coupling tube for use in connection with a conventional portable vacuum cleaner, such tube having a novel construction giving it an unusual amount of flexibility enabling it to successfully couple a paper bag to such a cleaner when the latter is of a pivoted handle type.

Another object is to provide an unsupported (non-inclosed) paper bag of sufficient strength and durability to meet the requirements of vacuum cleaner service.

Other objects of the invention will appear in the following detailed description of the invention, illustrated in the accompanying drawings, in which:

Fig. 1 is a side elevation of a vacuum cleaner embodying my invention.

Fig. 2 is a plan view of the dust collecting bag and coupled portions of the vacuum cleaner, parts being broken away to better illustrate the construction.

Fig. 3 is a transverse sectional view of the bag taken on the line 3—3 of Fig. 2.

Fig. 4 is an axial sectional view through the coupling and adjacent portions of the bag taken on the line 4—4 of Fig. 2.

Fig. 5 is a sectional view of the upper end portion of the bag taken on the line 5—5 of Fig. 2.

In the drawings, the reference character 1 denotes generally a vacuum cleaner having a pivoted handle, and a fan case discharge duct 2. My improved bag 3 is constructed of porous paper, each side wall of the bag and its neck 3b com-

prising inner and outer related blanks of such paper, lying face to face as shown in Fig. 3, their marginal edges bound, and the two side walls of the bag secured together and sealed by means of the reinforcing binding strips 4 secured by means of stitching 5 in channel shaped formation enclosing said marginal edges of the bag. The lower portion of the bag, indicated at 3a serves as a dust collecting pocket, being shaped to form a substantially cylindrical curve below the horizontal plane of the neck 3b when the bag is in a normal operating position in a vertical plane.

The bag has an inlet trap 10 which is formed of a flexible material, preferably cloth, in the form of a tube extending through the neck 3b, into the bag and along the upper longitudinal edge thereof to a point intermediate the two ends of the bag, preferably more than half way from the lower to the upper end of the bag. The trap is preferably secured by the line of stitching 5 along the major portion of its length between the inner side walls within the embrance of the reinforcing binding strip 4. The trap 10 is preferably formed with two flat sheets of material bound together at two edges as by the sewed binding 11. The lower end of the trap tube 10 is folded outwardly around the end of the neck 3b as at 6, and is sewed as at 12 against the outer face of the neck 3b.

The upper end 7 of the bag is closed by folding said end portion back upon itself as at 7' and securing either by stitching or by a clamp channel 8 of metal or the like. A spring 9 is hooked into an eye 8a on the channel 8, the spring in turn being suspended from the handle of a cleaner 1 as shown.

For connecting the bag to the exhaust duct 2, I provide a flexible tube which is constructed by covering a coil spring 19 with an outer covering of a highly flexible fabric 20 to which is vulcanized an inner coating of thin rubber.

The tube which is thus formed by the vulcanized fabric and rubber is extended beyond the ends of the spring 19 as at 21. These extended portions 21 are considerably thicker than the remainder of the tube so as to add rigidity to these end portions.

The lower end of the tube receives a sleeve 16 of a metal coupling 15 shaped to fit the exhaust tube of the particular cleaner to which the device is applied, and provided with some means such as the clasps 17 for detachably securing the coupling to said exhaust 2. The rubber or rubberized fabric inner face of the lower end portion 21 forms a dust tight connection with the outer surface of the sleeve 16, and a similarly dust tight

connection between the outer surface of the lower end portion 21 of the tube is formed by clamping the neck 3b of the bag around said lower end portion 21 as by means of a constriction clamp 24 having an operating lever 25 and a conventional latch device 26.

As indicated in Fig. 4, the resilient material of the lower projecting end portion of the tube allows the neck of the bag to be clamped tightly into such resilient material so as to give a very dust tight connection.

In the operation of the device, the bar is attached to the cleaner by first inserting the non-collapsible tube 19 through the neck of the bag into the trap 10, and thence clamping the neck of the bag by means of the clamp 24 on the lower end of the tube. The coupling 15 is then coupled to the exhaust of the vacuum cleaner and the spring 9 is hooked to the handle of the cleaner, whereupon the cleaner is ready for operation. It will be noted that the upper end 10a of the trap projects a substantial distance beyond the non-collapsible tube 19 so as to form a trap valve to prevent any dust dropping back down the tube after the operation of the cleaner has been stopped. At the same time, the trap 10 over the major portion of its length, is maintained in a distended position by the non-collapsible tube so that the accumulation of litter in the collecting bag 3a may not constrict the pasageway through the trap by pressing the side walls thereof together. Without the non-collapsible tube, the side walls of the trap would be so pressed together by the collected litter that when the bag became half full the suction of the cleaner would be very seriously impaired by such pressure.

The portion 10a projecting beyond the tube 18 is of such shortness that it forms no resistance to the passage of litter therethrough being maintained fully distended by the air current.

It will be understood that the trapping action of the trap tube 10 is due to formation of an annular pocket between it and the walls of the bag, in which refuse delivered from its upper end is trapped. Its lower end completely seals the neck of the bag against any dirt escaping therethrough. As long as the level of the collected refuse does not rise above the level of its upper end, it functions to prevent any dirt dropping back into the fan case when the power is shut off, irrespective of the valve action of its projecting unsupported upper end portion. Accordingly, the trap tube may be of the same length as, or slightly shorter than, the non-collapsible tube, without departing from the invention.

It is to be noted that the non-collapsible tube is connected to the bag only at the neck and remains free to slide longitudinally within the trap 10 in conformity to the bending of the trap and tube as the cleaner handle is moved up and down. A certain amount of such relatively longitudinal movement will occur during such bending, and if the tube and trap were rigidly connected during their whole length, this would create a resistance to the flexing of the bag which would be injurious to the bag.

A peculiar characteristic of the non-collapsible tube is that the greatest amount of bending which occurs in it will occur near the central region of the tube and it will bend in a fairly broad curve. Thus, although the paper bag also must flex as the handle of the cleaner is moved, it will not be allowed to flex at all in the immediate region of the neck, owing to the rigidity of the sleeve 16, and the major portion of such flexing will be dis-

tributed into the body portion of the bag, which can stand such flexing with much greater ease than the constricted neck thereof. Furthermore, the non-collapsible tube entirely prevents any sharp bending in the bag which would weaken the paper so as to allow rupture to occur.

The non-collapsible tube functions to constrain the bag to bend in a broad curve, owing to the fact that the upper region of the trap 10 will engage the upper region of the tube 19 as the bag is lifted by the handle, and thereby flex the tube 19 upwardly along with the bag, and the bag will thereby flex in unison with the tube.

It may be further noted that the trap 10 prevents the accumulating litter from settling against the sides of the non-collapsible tube. Thus the latter, which is removed from successive paper bags as the latter are filled and thrown away, and used over and over again, is kept clean and free from any accumulation of dirt on the outside which would be distasteful to the housewife. In addition, the protection of the tube against becoming embedded in the collected litter avoids any possibility of difficulty of removal of the tube from the bag by reason of its being embedded in such litter.

The successive layers of paper in the bag, from one side to the other, are indicated in Fig. 2 by the reference characters 3c, 3d, 3e and 3f.

A further advantage which may be noted with respect to the invention is this: The dust is projected into the bag in the upper region thereof so that the accumulation of litter in the lower region of the bag does not in any way interfere with the projection of the material into the bag. Only when the bag has become filled to the top will there be any tendency for the litter to obstruct the discharge of additional litter into the bag.

I claim as my invention:

1. In a vacuum cleaner having a discharge duct and a handle, the combination with said discharge duct of a porous paper bag having a neck connected to said discharge duct and suspended from the handle, a trap of flexible material inside of said bag communicating with the neck thereof and extending to a substantial height within the bag, and a flexible non-collapsible tube also connected to said discharge duct and extending upwardly within said trap to a point adjacent the upper end thereof, said tube being connected to said trap at the neck of the bag only and withdrawable therefrom.

2. In a vacuum cleaner having a discharge duct and a handle, the combination with said discharge duct of a porous paper bag having a neck connected to said discharge duct and suspended from the handle, a trap of flexible material inside of said bag communicating with the neck thereof and extending a substantial distance into the bag, and a flexible non-collapsible tube also connected to said discharge duct and extending upwardly within said trap a major portion of the length thereof, said tube being unconnected to said trap except at the neck of the bag and serving to distribute the major portion of any flexing that may be enforced upon the bag into the body region of the bag through the medium of said trap.

3. In a vacuum cleaner having a discharge duct and a handle, the combination with said discharge duct of a non-collapsible flexible tube the lower end of which is detachably connected to said duct, a porous paper bag having an in-

5. A dust trap for vacuum cleaners having at one end a neck for attachment to a cleaning device, each wall of said trap and neck comprising inner and outer related paper blanks, the marginal portions of said blanks along their side edges being in engagement and enclosed in a reinforcing binding strip and said strip and said portions being connected in sealed relation, and a dust trap formed of flexible material disposed between said inner blanks and extending at its outer end into said neck, said trap extending into said trap to a point remote from said neck and having its outer longitudinal side secured to the adjacent connected marginal portions of said blanks to support it axially of said neck and the material of said dust trap being extended through said neck and folded back into engagement with and secured to the exterior walls thereof.
6. A dust trap for vacuum cleaners having at one end a neck for attachment to a cleaning device, each wall of said trap and neck comprising inner and outer related paper blanks, the marginal portions of said blanks along their side edges being in engagement and enclosed in a reinforcing binding strip and said strip and said portions being connected in sealed relation, a dust trap formed of flexible material disposed between the inner blanks and disposed axially of said neck and extending into said trap to a point remote from said neck and having its outer longitudinal side secured to the adjacent connected marginal portions of said blanks to support said trap axially of said neck, and a non-collapsible flexible tube within said dust trap, one end of said tube fitting into said neck and adapted to removably engage an attaching element and the other end of the tube terminating within but adjacent the inner end of said dust trap.
7. A dust trap for vacuum cleaners having at one end a neck for attachment to a cleaning device, each wall of said trap and neck comprising inner and outer related paper blanks, the marginal portions of said blanks along their side edges being in engagement and enclosed in a reinforcing binding strip and said strip and portions being connected, and a dust trap formed of a flexible material disposed between the inner blanks and having one end extending into said neck, said trap extending from said neck into said trap to a point remote therefrom and
8. A dust trap for vacuum cleaners having at one end a neck for attachment to a cleaning device, each wall of said trap and neck comprising inner and outer related paper blanks, the marginal portions of said blanks along their side edges being in engagement and enclosed in a reinforcing binding strip and said strip and said portions being connected in sealed relation, a dust trap formed of flexible material disposed between the inner blanks and extending at its outer end into said neck, said trap extending into said trap to a point remote from said neck and having its outer longitudinal side secured to the adjacent connected marginal portions of said blanks, and a non-collapsible flexible tube within said dust trap, one end of said tube fitting into said neck and adapted to removably engage an attaching element and the other end of the tube terminating within but adjacent the inner end of said dust trap, said tube throughout its length serving to reinforce said trap and dust trap.
9. In a vacuum cleaner having a discharge duct and a handle, the combination with said discharge duct of a porous paper bag having a neck connected to said discharge duct and suspended from the handle, a trap of flexible material inside of said bag communicating with the neck thereof and extending to a substantial height within the bag, and a flexible non-collapsible tube also connected to said discharge duct and extending upwardly within said trap a major portion of the length thereof, said tube serving to distribute the major portion of any flexing that may be enforced upon the bag into the body region of the bag.
10. In a vacuum cleaner having a discharge duct and a handle, the combination with said duct of a porous paper bag suspended from the handle and having a neck receiving the discharge from said duct, a freely flexible non-collapsible tube connected at one end to said duct and extending a substantial distance into the bag, and means attached to the bag and adapted to engage said tube at a distance from the duct, when said bag is raised by said handle and to thereby flex said tube upwardly whereby said bag is constrained to flex in a broad curve in unison with said tube, and sharp bending at the neck avoided.
11. In a vacuum cleaner having a discharge duct and a handle, the combination with said duct of a porous paper bag suspended from the handle and having a neck connected to said duct, a trap of limp, flexible material, incapable in itself of remaining distended under the collapsing pressure of accumulated refuse surrounding it, said trap communicating with the neck of the bag and extending to a substantial height therein, and a flexible, non-collapsible tube also connected to said discharge duct, extending upwardly within said trap to a point adjacent the upper end thereof, and serving to hold at least a major portion of said trap in distended condition, said tube being withdrawable from the trap.

WILLIAM P. HUNSDORF.
